HOLLIS H. HARRIS, OF LORAIN, OHIO, ASSIGNOR OF ONE-HALF TO WALTER L. HILLER,
OF LORAIN, OHIO.

DEVICE FOR REMOVING THREADED NUTS.

1,104,497.

Specification of Letters Patent.

Patented July 21, 1914.

Application filed January 31, 1914. Serial No. 815,597.

To all whom it may concern:

Be it known that I, HOLLIS H. HARRIS, a citizen of the United States, residing at Lorain, in the county of Lorain and State of Ohio, have invented a certain new and useful Improvement in Devices for Removing Threaded Nuts, of which the following is a full, clear, and exact description, reference being had to the accompanying drawings.

This invention is a device for removing threaded nuts from long threaded members such, for example, as bolts, valve stems of pneumatic tires, etc., and the general object is to provide such a device whereby this may be done quickly and easily. It has heretofore been the common practice to remove nuts from such threaded members by a hand wrench or with the fingers, when loose enough to permit, but this process is slow and laborious at the best, while with my device threaded nuts may be rapidly removed from such threaded members.

Other objects are to provide a device which may be cheaply manufactured, which may be durable and efficient, and convenient to operate.

A convenient embodiment of my invention is shown in the accompanying drawings, and hereinafter more fully described in connection therewith, the essential characteristics being set forth in the claims.

In the drawings, Figure 1 is a side elevation of my device showing the valve stem of a pneumatic tire in a position to have a nut removed therefrom; Fig. 2 is a side elevation looking toward the wrench members of the device; Fig. 3 is a vertical longitudinal section through the wrench members; Fig. 4 is a section taken on the line 4—4 of Fig. 3; Fig. 5 is a section taken on the line 5—5 of Fig. 1; Fig. 6 is an end elevation of the wrench members.

Referring to the drawings, 10 indicates a suitable bracket-like frame having a suitable base 11 by which it may be secured to a support. This frame rigidly carries at its upper end a stub shaft 12 extending outwardly at one side of the frame, and as shown, this is secured in place by a set screw 13. Rigidly mounted on this shaft is a bevel gear 14 adapted to be rotated by a suitable crank 15 secured to the hub of the gear and to a projecting lug 16, and having a suitable handle 18. The gear is prevented from outward

movement on the shaft 12 by any suitable means, such as a pin 19, shown in Fig. 2.

Meshing with the gear 14 is a comparatively small pinion 20 having portions on its hub cut away, forming in effect, clutch teeth 21, adapted to engage similar projections or clutch teeth 22 on the end of a tubular wrench member 24, thereby causing it to rotate with the pinion. This tubular member 24 is carried on a stub shaft 25 having a reduced shank 26 fitted into a socket 27 in the frame and secured there by a suitable set screw 28. The pinion 20 is carried by this member, 25, being rotatable on a suitable bushing 29 which is provided with a flange 30 forming a shoulder engaging the gear. 70 A shoulder 31 formed on the member 25 engages the other end of the pinion and acts with the flange 30 to prevent longitudinal movement of the pinion. At the other end this tubular member has a contracted portion 35 in which is formed the angular opening 36, adapted to fit any desirable size or shape of nut. When the crank 15 is rotated, the tubular member 24 will be rotated through the gear and pinion described, and 80 any nut fitted into the angular opening 36 will be rotated with this member 24. Accordingly, it is only necessary to insert the nut in the opening 36, such as shown at 38, allowing the threaded member to extend 85 either into the member 34 or outwardly, and hold this threaded member against rotation, then rotate the crank in the proper direction to remove the nut. The difference in the diameter from the gear and pinion may be 90 such as to multiply the movement of the hand crank or any other power which may be used on the gear 14, in the desired relation thereby providing for the nut being rotated much faster than would be possible 95 in the ordinary way.

In the particular form shown in the drawings, to the exact construction of which I do not wish to be limited, I have shown a means for holding the threaded member 100 against rotation, which is as follows: The nut 38 is shown on the threaded exterior of a stem 40 such as are commonly used in pneumatic tires, particularly in automobile tires. This stem 40 has the usual enlarged 105 head 41 on the interior of the rubber 42, forming the usual inner tube of such a tire. These stems are usually flattened on two

sides as indicated at 43. These flattened sides engage flattened portions 44 in a contracted opening 45 in the outer end of a tubular member 46, which is rigidly mounted 5 within the member 24. As shown, this member 46 has a reduced shank 48 fitted into a socket in the end of the member 25. The member 25 is provided with notches 49 adapted to be engaged by lugs rigid with 10 the member 46 thereby holding it against rotation while allowing it to be readily removed from the member 25, when the tubular member 24 is removed. The member 46 has an internal bore 50 for the greater portion 15 of its length, adapted to receive the threaded member or stem. The stem is slidably engaged in the contracted opening 44, and as the nut 38 is rotated to remove it from the stem 40, this stem slides outwardly 20 until it is free from the nut. The member 24 may be removably secured to the member 25 by any suitable means. As shown I have provided a thumb screw 52 having its inner end sliding in an annular groove 53 as it is 25 rotated, thereby preventing the member 24 moving longitudinally on the member 25. This member being removable provides for having any desired number of members 24, each having a different size of angular opening 26, adapted to fit different nuts, and the member 46 being removable from the member 25, provides for having a number of these members each adapted to engage various shapes and sizes of threaded members. 30 It will be seen that the device might readily be arranged to rotate the threaded member, while holding the nut, and still accomplishing the same results, if it were desired. It is to be understood that this is 35 within the scope of my invention.

From the foregoing description it will be seen that I have provided a device particularly useful for quickly and easily removing threaded nuts from threaded members, and 45 it will also be seen that such a device in the form shown and described, may be cheaply constructed and will be very durable and efficient in operation.

Having thus described my invention, what 50 I claim is:

1. In a device of the character described, the combination of a member having a socket engaging a nut, a rigid second member in fixed axial alinement with said socket 55 adapted to slidably engage the member on which said nut is threaded, gearing attached to said members, and means attached to said gearing whereby one of the members is rotated with relation to the other.
2. In a device of the character described, the combination of a tubular member having a socket engaging a nut, a member in fixed axial alinement with the tubular member 60 adapted to slidably engage the member on which the nut is threaded, each of said mem-

bers being adapted to prevent the article engaged thereby from rotating in relation thereto, and means for rotating one of these engaging members with relation to the other whereby the nut is removed from its 70 threaded member.

3. In a device of the character described, the combination of a tubular member having a non-circular socket adapted to engage a nut, a tubular member in fixed axial alinement with said socket having means for slidably engaging the member on which the nut is threaded preventing its rotation with relation with said last named member, allowing it to slide out from the same, gearing attached to one of said tubular members, and means for rotating said gearing whereby one of the tubular members is rotated with relation to the other. 75 80

4. In a device of the character described, the combination of a tubular member having a non-circular socket adapted to engage a nut, a tubular member within said tubular member having a flattened portion adapted to engage a flattened portion on the member on which said nut is threaded and prevent its rotation with relation to such member, but allowing a sliding movement therein, means on which one of said tubular members is rotatably mounted, and means for causing 90 it to rotate with relation to the other. 95

5. In a device of the character described, the combination of a tubular member having a non-circular socket adapted to engage a nut, a tubular member within said tubular member having an opening with a flattened side adapted to engage a flattened side on the member on which said nut is threaded, means for holding said tubular member against rotation, a gear in axial alinement with said tubular members, means connecting said gear with the first mentioned tubular member, a gear meshing therewith, and means for rotating said last named gear. 100 105

6. In a device of the character described, the combination of a tubular member having a contracted portion at one end made angular to engage a nut, a tubular portion within said tubular member having an opening with a flattened side adapted to engage a flattened side on the threaded member carrying the nut, a shank on said last named tubular member, a socket removably carrying the same, a bearing on which said first tubular member is rotatable, means for securing it thereto and allowing its removal therefrom, a gear connected with said last mentioned tubular member, a gear meshing therewith, and means for driving said last mentioned gear. 110 115 120 125

7. In a device of the character described, the combination with a member for engaging a nut, of means for slidably engaging the member on which the nut is threaded, gearing whereby one of the engaging means 130

is rotated with relation to the other, said means for engaging the member on which the nut is threaded being so arranged as to allow the same to slide therefrom as the nut is rotated to be removed.

5 8. In a device of the character described, the combination of a fixed member having a socket with a non-circular portion adapted to slidably engage a non-circular portion of

10 a threaded member, a rotatable member in fixed axial alinement with said socket member adapted to non-rotatably engage a nut on said threaded member, and means for rotating the nut-engaging means.

15 9. In a device of the character described, the combination of a fixed member having

an axial socket, a sleeve fitting over said socket and having an end extending over the fixed member and adapted to non-rotatably engage a nut, said first mentioned socket 20 having a flattened portion adapted to engage a flattened portion on the member to which the nut is threaded, a gear for driving said sleeve, a second gear, and means for rotating them.

25 In testimony whereof, I hereunto affix my signature in the presence of two witnesses.

HOLLIS H. HARRIS.
